UNITED STATES PATENT OFFICE.

GEORGE L. REICHHHELM, OF NEW HAVEN, CONNECTICUT.

GAME.

1,223,520.

Specification of Letters Patent. Patented Apr. 24, 1917.

Application filed January 5, 1915. Serial No. 656.

To all whom it may concern:

Be it known that I, GEORGE L. REICHHHELM, a citizen of the United States, residing at New Haven, in the county of New Haven and State of Connecticut, have invented certain new and useful Improvements in Games, of which the following is a specification.

This invention relates to improvements in games, and more particularly to a game consisting of an impelling member and a receiving member, the latter being provided with a plurality of pockets or apertures located in a wall and arranged to receive a missile when the latter is properly projected by the impelling member. I utilize this game, for example, as an indoor golf game by providing nine apertures or pockets as receiving members, as will be more fully explained below.

The primary object of my invention is to provide novel impelling mechanism particularly adapted for use in a game of the character above referred to. My invention will be more fully described hereinafter with reference to the accompanying drawing in which the same is illustrated as embodied in a convenient and practical form, and in which:

Figure 1 is a perspective showing my improved game mounted on a table or the like;

Fig. 2 is a side elevation of the impelling member;

Fig. 3 is an end elevation of the same;

Fig. 4 is a plan view of the same; and

Fig. 5 is a perspective of the discharge member.

Like numerals refer to like elements throughout the drawings. In Fig. 1, 10 designates generally a table or the like upon which may be mounted, at suitable distances, what I term the receiving member 11 and an impelling member 12.

The impelling member comprises, in the form shown, a main base plate 12^a upon which is mounted a second plate 12^b, the latter being attached to the former by means of a wing nut and bolt 12^c in such wise that plate 12^b may be rotated about to desired position and clamped in such positions by means of the wing nut. Carried by the plate 12^b is the frame member 12^w comprising a base portion 12^d, a tall upstanding arm or leg 12^e and a shorter arm 12^f. Extending through suitable apertures in arms 12^e and 12^f is the horizontal rod 12^g terminating at

one end in the looped portion 12^h having the sharpened extremity 12ⁱ adapted to engage with corrugations or ridges 12^j in the outer face of arm 12^f, see Fig. 2 for example. A 60 track member is provided, the same comprising a trough or angle piece 12^k provided with the strip 12^l attached thereto at one extremity and extending thereover, as shown in Figs. 3 and 4, for example. The rod 12^g is secured to and passes through this strip 12^l, and it will be apparent that rotation of the rod 12^g will operate to adjust vertically the track 12^k. A spring 12^m is located around the rod 12^g between the strip 12^l and arm 12^f, this spring serving to maintain the end 12ⁱ and portion 12^h of the rod in contact with ridges 12^j, as will be apparent. I further provide a discharge member 12ⁿ, see Fig. 5 for example, having a striker portion 12° and a rearwardly extending arm 12^p for engagement by the hand of the operator. The main portion 12^q of the discharge member 12ⁿ extends upwardly from the striker 12° and terminates in the bent over or looped 70 portion 12^r. The portion 12^q is pivotally attached adjacent its upper extremity to the arm 12^s of the frame by means of the bolt and nut 12^t, or the like. The extremity of the downwardly looped portion 12^r carries a 80 pin or stud 12^u to which is attached one end of the spring 12^u, the other end thereof being attached to the pin 12^v carried by the lower portion of arm 12^s of the frame. It will be apparent that movement backwardly 90 of the discharge member 12ⁿ will be resisted by the distention of the spring 12^u and when released the striker 12° will be moved toward the track 12^k with considerable force.

In the use of this game the ball or missile 13, such as a ping pong ball, or the like, is provided and the person playing the game places this ball 13 on track 12^k, adjusting the inclination of the same as desired. The plate 12^b may then be pivoted or moved to the position desired by the player and clamped in such position, and these adjustments having been made to suit the player the latter may draw the striker 12° back against the action of spring 12^u to the desired point and released, whereupon the ball or missile 13 will be projected by the striker 12° in a path similar to that indicated by the dotted line and arrow in Fig. 1, toward the receiving member 11. Assuming that the game is beginning, the player will endeavor to discharge the ball 13 through a predetermined hole in

the receiving member, keeping count of the number of strokes required to accomplish this result and then endeavoring to accomplish the same result with a second hole, and 5 so on through the nine holes keeping track of the shots required for each hole and the total, as in the case of outdoor golf. By varying the distance between the impelling member and receiving member it will be apparent 10 that the difficulty may be increased or decreased and the number of apertures and the varying size of the same provides a similarity between my game and that of outdoor golf in that nine or eighteen, or 15 any multiple of nine holes may be played and the strokes required will generally vary according to the difficulty experienced. Competing players may compare their scores at the conclusion of each nine holes or 20 may alternate in shooting for the successive holes, as desired. Such rules as may be necessary to enhance or regulate competition between players may be provided.

It will be obvious that my device is susceptible 25 of many modifications and improvements and I do not wish to be restricted to the form shown or described beyond the scope of the appended claims.

What I claim is:—

30 1. In a device of the class described, a supporting frame provided with an upright arm, a track member located adjacent said arm, an impelling member pivotally attached to said arm, and a spring member extending between and attached to said impelling member and said frame to resist movement of said impelling member from its normal or rest position.

40 2. In a device of the class described, a frame provided with upwardly extending portions, a shaft journaled in said portions, a track member rigidly secured to said shaft, said shaft being adjustable to various positions to adjust the inclination of said track, 45 and means to maintain such shaft in adjusted positions.

50 3. In a device of the class described, a frame provided with upwardly extending portions, a shaft journaled in said portions, a track member carried by said shaft, and an impelling member comprising a striking portion and an arm, the latter being pivotally attached to one of said upright portions of said frame.

55 4. In a device of the class described, a frame provided with upwardly extending

spaced standards, a horizontal shaft journaled in said standards, a track member rigidly secured to said shaft, and an arm projecting radially from one end of said shaft and adjustably engaging the outer surface of the adjacent one of said standards for varying the inclination of said track.

5 In a device of the class described, a 65 base, a supporting frame pivotally carried thereby, said supporting frame being provided with an upright arm, a track member located adjacent said arm, an impelling member pivotally attached to said arm, and 70 a spring member extending between and attached to said impelling member and said frame to resist movement of said impelling member from normal or rest position.

6 In a device of the class described, a 75 frame, a pair of standards secured to and projecting upwardly from said frame, a horizontal shaft journaled in said standards, a track member carried by said shaft, an arm projecting radially from one end of 80 said shaft and adjustably engaging the outer surface of the adjacent one of said standards for varying the inclination of said track, and an impelling member comprising a 85 striking portion and an arm, the latter being pivotally attached to the other one of said standards.

7 In a device of the class described, a 90 base, a frame pivotally carried thereby, said frame being provided with upwardly-extending portions, a shaft journaled in said portions, a track member rigidly secured to said shaft, said shaft being adjustable to various positions to adjust the inclination 95 of said track, and means to maintain such shaft in adjusted position.

8 In a device of the class described, a 100 base, a frame pivotally carried thereby, said frame being provided with upwardly-extending portions, a shaft journaled in said portions, a track member carried by said shaft, and an impelling member comprising a striking portion and an arm, the latter being pivotally attached to one of said upright portions of said frame.

105 In testimony whereof, I have subscribed my name.

GEORGE L. REICHEL.
